APPARATUS FOR PACKING ARTICLES INTO CONTAINERS

William Geisler, Tenafly, N. J., assignor to Economic Machinery Company, Worcester, Mass., a corporation of Massachusetts

Application August 22, 1951, Serial No. 243,063

19 Claims. (Cl. 226—14)

1

This invention pertains to apparatus for filling containers, more specifically for preparing and introducing a filler unit into a container, for instance, a shipping carton.

In my copending application, Serial No. 106,824, filed July 26, 1949, for Method of Making Filled Packages, I have described the preparation of an embryo carton from a sheet material blank, the assembly of a plurality of articles with a spacer grid to form a filler unit, the introduction of this unit into the carton, and the subsequent closing and sealing of the carton—all as a continuous process, noting that the various steps of this process may each be carried out as a hand operation, if desired.

The present invention concerns a novel mechanism for making the filler unit and introducing it into the empty carton prepared to receive it.

Various methods have heretofore been used for introducing a plurality of articles, for example, bottles, into a shipping container. Customarily, shipping containers, such as cartons, are filled through the open top. Usually a spacer grid is employed to prevent contact of the articles with each other and to prevent the articles from shifting within the container. Sometimes the grid is first placed in the carton and the articles introduced one-by-one by hand into the grid spaces or pockets. Sometimes the articles are placed loosely in the empty carton and the grid is pushed down over them. Sometimes the articles are assembled with the grid and the carton is inverted and pushed down over the assembly and then turned right side up. These previous methods of filling the carton all require that the carton be open at its top (or alternately, at its bottom) which means that when the carton is filled and sealed, its top or bottom wall, or both, consist of overlapping flaps united by glue or metallic fasteners, thus providing an uneven bottom surface and a top or bottom which depends upon the strength of the fastening means to keep it closed.

The advantages of a carton, such as a shipping container, which can be filled through a side wall, have been pointed out in my aforementioned copending application, in particular, the fact that the top and bottom walls of such a carton may be unitary—presenting uninterrupted, smooth surfaces which facilitate the sliding of the carton along the floor or its movement on a conveyor—such unitary top and bottom walls affording the full strength of the sheet material to support the contents when the closed container is lifted and/or inverted. One object of the present invention is to provide improved apparatus for in-

2

roducing a filling charge into a carton which is open at its side (as distinguished from its top or bottom). A further object is to provide improved mechanism operative to receive articles, for instance, bottles from a supply and to arrange them in predetermined order to form a filler block of a size and shape substantially to fill the carton. A further object is to provide mechanism operative to introduce a filler unit comprising a predetermined number of articles assembled with a spacer grid into a carton open at its side. A further object is to provide mechanism operative to assemble a plurality of articles, received from a supply, to form a filler block while concomitantly introducing a previously prepared filler unit into a container. A further object is to provide mechanism, including means cooperable with an open-sided carton, to facilitate the introduction thereinto of a filler unit such as will fit snugly within the carton. A further object is to provide means operative to deliver articles in proper sequence and in a plurality of parallel paths to form the desired filler block. A further object is to provide means operative automatically to stop the operation of the mechanism in the event of failure of an empty carton to arrive at the filling position, or in the event of failure of articles to arrive from the supply in orderly succession and at a rate sufficient to form a complete filler block. Other and further objects and advantages of the present invention will be pointed out in the following more detailed description and by reference to the accompanying drawings wherein:

35 Fig. 1 is a diagrammatic plan view of apparatus useful in the making, filling and sealing of a shipping package, and showing the location of the filling mechanism of the present invention with respect to other operative elements of such apparatus;

Fig. 2 is a plan view, to larger scale, of the carton-filling mechanism of the present invention;

Fig. 3 is a view similar to Fig. 2, omitting certain parts, and illustrating a modification;

45 Fig. 4 is a diagrammatic side elevation, partly in vertical section, of the apparatus shown in Fig. 2, the parts being in the position which they occupy when a filler unit is about to be introduced into the empty carton;

50 Fig. 5 is a view similar to Fig. 4 but showing the elevator for the filler unit in its depressed or receiving position, and showing the carton as having received its filler unit;

Fig. 6 is a side elevation, to larger scale, illustrating one desirable arrangement for agitating

55

the articles as they approach the filler mechanism to prevent jamming of the articles as they move along;

Fig. 11 is an elevation looking from the right-hand side of Fig. 8;

Fig. 12 is a vertical section through the elevator, shown in loading position;

Fig. 13 is a fragmentary plan view of the elevator;

Fig. 14 is a fragmentary section, on the line 14—14 of Fig. 13; and

Fig. 15 is a wiring diagram illustrative of an automatic control for the elevator operating clutch.

The unit-forming and carton-filling mechanism of the present invention, while of broader utility, is herein illustrated as forming a part of an apparatus whereby a carton is made from a blank which is folded, and overlapping portions of the blank are stapled to form an embryo carton open at its side. This embryo carton is delivered to the filling device, herein more specifically described, and after filling, is delivered to a closing mechanism whereby its open side is closed and then sealed. Such a carton making and filling apparatus is illustrated diagrammatically by way of example in Fig. 1 where the numeral 1 designates a magazine for blanks, of cardboard, or the like, suitably shaped to form the desired carton. These blanks are conveyed, preferably automatically to a station 2 at which they are partially folded, the partially folded blank when moving to a station 3, which may be an idle station, and then to a station 4 at which a further manipulation of the blank takes place preparatory to advancing it through a stitching zone 5 where certain of the end-forming flaps of the blank are permanently united, for example, by staples. The embryo carton thus formed continues to advance to the station 6 at which its direction of movement is changed, the carton being carried along by conveyor means through a station 7, which may be an idle station, and then to the station 8 where the filling charge or unit is formed and introduced into the carton. From this station 8 the filled carton, with its open side still open, advances through a station 9 where glue may be applied to some of its parts and then to a station 10 where the open side is closed. From this station the filled and closed carton passes to a station 11 where it may be subjected to pressure or confinement while the adhesive which unites its closing elements to the other parts, is setting, the completed and filled carton then being removed from the station by any desired conveying means 11.

The mechanism of the present invention is located at the station 8. Figs. 2, 4 and 5 illustrate diagrammatically the essential parts at this station 8.

The carton is advanced from the station 7 to the station 8 by appropriate means, for example a conveyor chain or intermittently acting pusher dogs, which move it along a guideway comprising parallel, spaced horizontal rails suitably supported at the desired elevation. At the time of its ar-

rival at the station 8, the carton C comprises the parallel spaced top and bottom members T and B (Fig. 5) the rear wall R, end walls, and the front closure flaps E and F. Before arriving at the station 8, the flaps E and F have been bent upwardly and downwardly, respectively, as shown in Figs. 4 and 5, by appropriate means, for example stationary plows, so that, as the carton arrives at the station 8, its open front is wholly unobstructed.

As one element of the filling apparatus at the station 8, there is provided a stationary funnel member 14 of a transverse sectional shape and size approximating that of the interior of the carton C. Preferably this stationary funnel member tapers in width, as shown in Fig. 2, so that its narrower end may readily be entered within the open front of the carton. Preferably, the top wall of this funnel flares upwardly as shown at 14a (Fig. 5) to facilitate the entrance of the filler unit. The bottom wall P of this stationary funnel 14 is supported so that its upper surface inclines downwardly and to the left, as seen in Fig. 8, so that it lies in substantially the same plane as the upper surface of the bottom B of the carton as it is presented by the conveyor. As shown in Figs. 4, 5 and 8, that portion 12, 13 of the guideway along which the cartons travel is mounted to tilt about an axis at the point X (Fig. 8) and as the empty carton arrives at station 8 (Fig. 4) it stands on the tilted portion of the guideway so that its bottom wall B is inclined. When the filler unit enters the carton, its weight restores the guideway 12, 13 to the horizontal (Fig. 8).

At the opposite side of the conveyor from the funnel 14 there is arranged a pusher device 15 designed to engage the outer surface of the rear wall R of the carton and, after so engaging said wall, to move to the left, as viewed in Fig. 4, so as to force the carton onto the smaller end of the funnel 14. When partially telescoped over the funnel, the carton is supported partially by the funnel and partially by the guideway element 12, 13.

The left-hand end of the funnel 14, as viewed in Figs. 4 and 5, is flush with what may be termed one wall V (Figs. 4 and 5) of an elevator well in which the elevator or vertically movable table 16 moves up and down. This elevator or table 16 is moved up and down by vertically reciprocating links 73b as hereinafter more fully described. At its upper limit of movement (Fig. 4) its upper surface is at substantially the same level as that of the left-hand edge (Fig. 4) of the bottom of the funnel 14.

While the elevator or table 16 dwells in this latter position, the filler unit, which then rests upon the upper surface of the elevator or table, is pushed into the funnel 14 and eventually into the carton by a pusher member 18 carried by rods 19 which are reciprocated horizontally by mechanism hereafter described.

The filler unit comprises a spacer grid 21 (Figs. 2, 4 and 5) which is usually made of cardboard comprising transverse and longitudinal interlocked members which collectively define a plurality of cells, each designed to hold one article, for example a bottle W, as here illustrated. This spacer grid is held by an operator so as to receive the charge of bottles W as the elevator rises, the spacer grid being pushed down so that its lower edge engages the upper surface of the elevator or table just prior to the advance of the pusher 18.

As shown in Fig. 5, the elevator 16 is in its lowermost position, this being its position for

receiving a charge of articles. For delivering the articles to the elevator, there is provided a conveyor, here shown as an endless belt, having the upper horizontal, article-supporting run 22 which is substantially level with the upper surface of the table or elevator 16 when the latter is in the receiving position, shown in Fig. 5. As here illustrated (Fig. 3) the carton contains four transversely extending rows of bottles with six bottles in a row and, in order to position the bottles properly on the elevator, fixed parallel guide rails 23 and 24 (Fig. 2) are provided. These guide rails extend longitudinally of the conveyor 22, the rails 23 being at the opposite edges respectively of the belt and the rails 24 being arranged between the rails 23, adjacent rails being spaced apart so as to provide six parallel paths or channels, each of a width approximating that of the diameter of one of the bottles W. The width of the elevator table 16, measured from right to left, as viewed in Figs. 4, 5 and 12, is such as to receive four rows of bottles.

In order to insure the proper distribution of bottles into the several parallel paths or channels leading to the elevator, an arrangement, such as that illustrated in Figs. 2, 6 and 7, may be employed. In this arrangement the intermediate partitions or rails 24 each terminates at a point 25. An agitator blade 26 or 26^a (Figs. 6 and 7) is arranged in line with one or another of the rails 24 just beyond the terminal point 25. These blades 26 and 26^a are arranged in alternation, the blades 26 being carried by arms 27 (Fig. 7) and the blades 26^a by arms 27^a. The arms 27 are fixed to a rock shaft 28 and the arms 27^a to a rock shaft 28^a. These rock shafts are interconnected by meshing gears 29 and 30 so that when one shaft rocks in one direction, the other rocks in the opposite direction. One of these shafts is provided with an actuating arm 31 which is connected by a link 32 to a crank pin 33, the rotation of which rocks the arm 31 and thus oscillates the blades 26 and 26^a simultaneously in opposite directions.

At the right hand side of the elevator, as viewed in Figs. 4 and 5, a row of detector devices 44 is arranged, one detector for each of the six rows of articles. As the leading article in each row engages the corresponding detector, a switch is closed. When all six switches are closed, the elevator starts to rise.

As shown in Figs. 4, 5, 8 and 12, the elevator is provided with a depending vertical guard plate, a gate 16^x which moves up and down with the elevator and which, when the elevator is up prevents accidental escape of articles from the conveyor into the elevator shaft.

Rearwardly of the blades 26 and 26^a there is provided a receiving chamber 36 (Fig. 2) into which the articles W are delivered, as here shown, from two guideways which receive the articles from any suitable source, for example, from a pair of labeling machines. In order to prevent jamming of the articles within the chamber 36 as they approach the entrances to the paths defined by the rails 24, the side walls 37 of the chamber 36 are pivoted, being urged inwardly toward each other by springs 38 and being limited in their outward movements by stops 39. The swinging of these arms outwardly is arranged to control valves which admit air to cylinders 40 containing pistons designed to actuate gate members 41, designed, at times, to extend across the parallel delivery channels 42 so as temporarily to stop the delivery of articles along said channels. Such an arrangement of gate mechanism

is more fully described in the application of Carter, Serial No. 43,827, filed August 12, 1948, to which reference may be had for further details.

In Fig. 3 there is illustrated a modified arrangement for distributing the articles W into the guide paths defined by the plates 23 and 24. In this arrangement, each member 24 terminates at a point 43 at the delivery end of a chamber 45 into which the articles are delivered through the guide channels 42^a. The floor of this chamber 45 consists of a plate which is supported for movement in the direction of the arrow A, Fig. 3, and this plate is vibrated back and forth in this direction at very high speed and with a small amplitude of vibration, for example, by electromagnetic means, so that the articles W within the chamber 45 are agitated and thus prevented from jamming as they approach the entrances to the guide channels between the plates 24. This arrangement of a shaker plate may be incorporated in the device shown in Fig. 2, if desired, such a plate then forming the floor of the chamber 36. Since shaker devices of this general type have been used for various purposes, it is unnecessary to describe in detail the electromagnetic means for vibrating the plate.

The actual mechanism, whereby the above operations are caused to take place, is disclosed more particularly in Figs. 8 to 14, inclusive. This mechanism comprises a rigid frame having spaced uprights 46 which may be castings and which are rigidly connected by transverse members 46^a or the like, the frame preferably having adjustable legs or supports 47 and 48 for leveling the apparatus and whereby its elevation may be varied to some extent in order, particularly, that the funnel 14 may be accurately adjusted relatively to the position of the carton C at the filling station. The funnel 14 is supported by brackets 50.

At the rear of the machine (Fig. 8) there is provided an adjustable support on which is mounted a drive motor 51. This motor drives a shaft 51^a, preferably with an interposed clutch device, whereby the shaft may be stopped, if desired, and on this shaft 51^a is mounted a pulley 52 which receives a belt 54 which drives a pulley 55 on a shaft 56 parallel to the motor shaft. A gear fixed to the shaft 56 drives a gear 57 mounted on a stub shaft 58 carried by the machine frame. This gear 57 meshes with a gear 59 normally free on the cam shaft 60 which is journaled in suitable bearings carried by the machine frame. Gear 59 may be connected, at times, to the shaft 60, by a one-revolution clutch of conventional type having the actuating arm 67^a which is operated by a solenoid D'.

A sprocket wheel on the shaft 56 drives a sprocket chain 61 which embraces a sprocket wheel fixed to a shaft 62 mounted at its opposite end portions in bearings carried by the frame. On this shaft is another sprocket wheel which drives a sprocket chain 63 which passes about a sprocket wheel on shaft 64 (Figs. 8 and 10) near the forward part of the machine. On this shaft 64 are mounted the drive rollers 65 (Fig. 10) for the conveyor, whose upper run 22 advances the articles toward the filling station.

A shaft 67 (Figs. 8 and 9) is fixed at its opposite ends in the side frame members 46, and on this shaft is mounted the hub 68 (Fig. 9) of a bell-crank lever having an arm 69 (Fig. 9) provided with a cam follower roll 70 which engages a cam groove in a cam disk 71 fixed to the shaft 60. The other arm 72 of this bell-crank lever

extends forwardly and downwardly (Fig. 8) and has a bearing 73 at its forward end (Fig. 11) which receives a transverse pin 73^a. A shackle of adjustable length connects the pin 73^a to the links 73^b, whose upper ends are pivotally secured to the elevator or table 16. Elevator guiding rods 17, fixed to opposite edges of the table, slide in vertical bearings 14 carried by the machine frame.

Mounted on the shaft 67 (Fig. 9) is the hub 75 of another bell-crank lever, having a rearwardly-directed arm 76 provided with a cam follower roll 77, which engages a cam groove in a cam disk 78 fixed to the shaft 60. This bell crank also has a downwardly-extending arm 79 (Fig. 8) to whose lower end is pivotally connected the rear end of a rigid rod 80 which extends upwardly and forwardly and is pivotally connected by a pin 81 to the lower arm 82 of a bell crank pivoted at 83 to a bracket fixed to the conveyor structure along which the carton C is advanced to the filling station. The arm 82 of this bell crank is rigidly connected to an upwardly-extending arm or arms 85 to whose upper ends is connected the pusher device 15 by means of which the carton is advanced so as to be partially telescoped over the filler funnel, as above described.

Near the rear of the machine there is a stub shaft 86 (Fig. 9) fixed to the machine frame and projecting outwardly, and on which is mounted a hub 87 carrying a long lever arm 88 (Fig. 8) extending forwardly and having, at a point intermediate its ends, a pin carrying a cam follower roll 89 which engages a cam groove in a cam disk 90 fixed to the shaft 60. To the forward end of the lever arm 88 are pivotally connected the lower ends of parallel links 91 (Fig. 10) whose upper ends are pivoted to a vertically movable rack bar 92 (Fig. 8) mounted to slide vertically in bearings carried by the machine frame. This rack bar meshes with a pinion 93 mounted on a shaft 94 (Fig. 8) having, at opposite sides of the machine, gears 95 which mesh with horizontally movable rack bars 96, mounted in suitable guides 97 carried by the machine frame, and whose rear end portions preferably engage hold-down gears 98 journaled to turn on stub shafts carried by brackets 99 forming parts of the machine frame. At their forward ends the rack bars 96 are connected to rods 19 which carry the pusher 15, by means of which the filler unit is advanced from the elevator and through the funnel 14 into the empty carton.

The elevator or table 16 is a grill-like structure (Figs. 13 and 14) comprising a series of bars 100 separated by slots 101. The bars 100 form the actual supports for the articles W, there being one of these bars for each row of articles to be placed in the carton.

At a point below the receiving position of the elevator, as shown in Fig. 5, there is arranged a support (Figs. 11 and 12) consisting of a pair of spaced parallel bars 102 which carries a series of rigid, vertical plates 103, each of these plates being registered with one of the slots 101 in the elevator. When the elevator is in the receiving position of Fig. 5, these plates 103 extend up through the slots 101, each one of the plates 103 being aligned with one of the rails 24 which define the guideways for the articles as they approach the filling station. Thus, as the articles are advanced onto the elevator, they are kept in proper alignment until the foremost article in each row engages the detector 44 whereupon the conveyor drive is stopped. As the elevator rises,

the plates 103 remain stationary so that, when the elevator has risen to the discharge position, shown in Fig. 4, there is nothing to interfere with the advance of the pusher 15 as it discharges the articles from the elevator table.

In Fig. 15 there is diagrammatically illustrated an electric circuit by means of which the rise and descent of the elevator is automatically controlled. This circuit includes in series the several switches 44^a which are actuated by the detectors 44 in response to the loading of articles onto the elevator. In series in the same circuit is the switch K (Fig. 4) which is closed by the presence of an empty carton properly disposed in load-receiving position. Also in this circuit is a switch K' (Fig. 4) which is closed whenever a spacer grid is properly positioned in the holder 20 to receive a load of articles carried by the rising elevator. In the same circuit is a switch K², which is normally closed, but which is opened by a filled carton in the position shown in Fig. 3. Until the filled carton has been advanced from the loading station 8 toward the station 9, the switch K² remains open and the loading mechanism is idle, thus preventing a second charge from being delivered into a filled carton. In series in the same circuit is the solenoid D' which, when energized, allows the driving clutch of the elevator mechanism to act. Until all of the several switches in the series are simultaneously closed the elevator remains in the down or load-receiving position. When all of the switches in the series are closed the elevator rises to the load-delivering position. As the elevator starts to rise, the circuit is broken at the switches 44^a, but the clutch which drives the elevator is of conventional one-revolution type so that when once engaged, it makes a complete rotation before stopping even though the actuating circuit is broken. The cam which drives the elevator is so contoured as to hold the elevator stationary at the load-delivering position for a sufficient time interval to allow the pusher to move the load into the funnel, whereupon the elevator descends to the load-receiving position where it dwells until the circuit is again closed.

In the operation of the machine, and assuming that articles are being supplied from a suitable source through the guide channels 42 or 42^a and that the articles are being properly distributed into the paths defined by the fixed rails 23 and 24, and assuming that the elevator is in the low or receiving position of Fig. 5, the articles W are moved along by the conveyor 22, as here shown, in six parallel rows and continue until the foremost article W' (Fig. 5) in each row engages the corresponding feeler or detector member 44. This advance of the articles continues until the individual feeler 44, corresponding respectively to each of the six rows, has been engaged by one of the articles. When all of the feelers 44 have thus been contacted and assuming that all of the switches K, K' and K² are closed, the circuit is completed and the elevator 16 rises. As it rises, carrying with it the block 45 of articles (in this particular case, 24 articles), the last of the articles W² to come to rest on the elevator moves up past the next succeeding article in the corresponding path, holding the latter article back until it is engaged by the depending guard plate 16^x. This guard plate holds back the articles which the conveyor 22 is constantly urging forward and continues to hold them back as the elevator rises until the elevator reaches the delivery position shown in Fig. 4.

At some time prior to the completion of the rise of the elevator, the arm 85 has been rocked by action of the cam 78 so as to push the empty carton C to the left, as viewed in Fig. 4, until its open end partially telescopes over the right-hand end of the funnel 14, as shown at C', Fig. 4, and until it engages and actuates the detector which controls switch K. Prior to the rise of the elevator, the operator has placed a spacer grid 24 above the charge of articles on the elevator and has pushed it down until its lower edge is but slightly above the level of the floor of the funnel 14. In so doing, the detector which controls switch K' is actuated to close the switch, the switch K² being normally closed. The circuit being completed, the elevator rises, as above described, and one of the articles W enters each respective cell of the spacer grid. As soon as the elevator reaches its uppermost position, as determined by the shape of the groove in the cam 70 (which is shaped to cause the elevator to dwell at this uppermost position for a short time) the cam 90, through the connections described, causes the pusher 18 to be advanced toward the right so that it engages the block of articles resting on the elevator and advances the block with the spacer grid, as a unit, into the open end of the funnel 14. The upwardly flaring part 14a (Fig. 4) of the top wall of the funnel 14 assists in crowding the spacer grid down, if it is not in proper position until its lower edge rests upon the floor of the funnel. As soon as the filler unit, comprising the articles W and the spacer grid, has been fully entered into the funnel, the elevator immediately starts down, and as soon as it reaches the receiving position (Fig. 5) where it dwells for the proper interval, the conveyor 22 advances more of the articles W onto the elevator. While this is taking place the pusher 18 continues to move to the right until the filler unit has been pushed completely through the funnel and into the carton C. The pusher 18 then continues still further so as to restore the carton, with its filler unit, to the position shown in full lines in Fig. 4. Preferably the pusher 15 normally occupies the idle position shown in Fig. 5, so that it forms a stop to limit the movement of the filled carton to the right, thus insuring its proper position on the conveyor. The pusher 18 now retracts slightly, for example, one-half inch, and dwells to constitute a guide for the filled carton as the latter starts to advance toward the station 9, Fig. 1. As the loaded carton comes to rest on the rails 12, 13, its weight depresses the rails, in opposition to a spring Z (Fig. 8) which tends to tilt them to the position of Fig. 4. As the rails are then depressed, the switch Z² is opened. When the filled carton leaves the station 8, the switch Z² is again closed, and the pusher 18 now completely retracts to its rearmost position and the elevator starts to rise, thus completing the cycle. It may be noted that, by this arrangement, the actual introduction of the filler unit into the carton is taking place while a succeeding filler unit is being accumulated on the elevator at the low level. Thus, the time consumed in filling the carton is materially reduced, as compared with arrangements in which the articles, designed to form the filler unit, are accumulated and immediately loaded into the carton, while succeeding articles remain at rest until the loading operation is complete.

While one desirable embodiment of the invention, with slight modification thereof, has herein been illustrated and described by way of ex-

ample, it is to be understood that the invention is broadly inclusive of any and all modifications falling within the scope of the appended claims.

I claim:

- 5 1. In combination in apparatus for introducing a filler block into a container, said block comprising independent, like articles arranged in parallel rows, all of which contain the same number of articles, means defining parallel pathways in number equaling the number of rows in the filler block, means for moving articles along each pathway, a vertically movable block carrier having a horizontal upper surface which at times is disposed in a receiving position such as to receive articles delivered from all of the pathways, a detector corresponding to each pathway, each detector being designed to respond when articles, in number sufficient to form one row of the block, have been delivered onto the carrier from the corresponding pathway, means operative to move the carrier from receiving position to a delivery position only after all of the detectors have so responded and means for pushing the block of articles, as a unit, from off the carrier while the latter is in the delivery position.
- 10 2. In combination in apparatus for introducing a filler block into a container, said block comprising independent, like articles arranged in parallel rows, all of which contain the same number of articles, means defining parallel pathways in number equaling the number of rows in the filler block, means for moving articles along each pathway, a vertically movable block carrier having a horizontal upper surface which at times is disposed in a relatively low, receiving position such as to receive articles delivered from all of the pathways, a detector corresponding to each pathway, each detector being designed to respond when articles, in number sufficient to form one row of the block, have been delivered onto the carrier from the corresponding pathway, means operative to move the carrier vertically up from receiving position to a delivery position when all of the detectors have so responded, means to prevent further delivery of articles from the several pathways until the carrier is again in position to receive them, and a horizontally movable pusher for discharging the block of articles, as a unit, from the carrier while the latter is in the delivery position.
- 15 3. In combination in apparatus for introducing a filler block into a container, said block comprising independent, like articles arranged in parallel rows, all of which contain the same number of articles, means defining parallel pathways in number equaling the number of rows in the filler block, means for moving articles along each pathway, a vertically movable block carrier comprising a horizontal grid which at times is disposed in a receiving position such as to receive articles delivered from all of the pathways, a detector corresponding to each pathway, each detector comprising a movable part which is moved when articles, in number sufficient to form one row of the block, have been delivered onto the carrier from the corresponding pathway, means operative to move the block carrier vertically from receiving position to a delivery position when all of the detectors have so responded, the carrier having a gate which extends across the delivery ends of the several pathways whenever the carrier is moved from receiving position, and means for pushing the block of articles, as a unit, from off the grid while the carrier is in the delivery position.

4. In combination in apparatus for introducing a filler block into a container, said block comprising independent, like articles arranged in parallel rows, all of which contain the same number of articles, means defining parallel pathways, in number equaling the number of rows in the filler block, means for moving articles along each pathway, a vertically movable carrier having a horizontal upper surface of a size and shape to receive and to support a block of articles, said carrier, at times, being disposed with its upper surface at a level to receive articles from the several pathways, and means operative, when sufficient articles have been delivered from each pathway to constitute the complete block, to move the carrier with the block of articles to a different level.

5. In combination in apparatus for introducing a filler block into a container, said block comprising independent, like articles arranged in parallel rows, all of which contain the same number of articles, means defining pathways, in number equaling the number of rows in the filler block, means for moving articles along each pathway, a vertically movable elevator having a horizontal upper surface of a size and shape to receive and to support a block of articles, said elevator, at times, being so located with respect to the delivery ends of the pathways that articles from the pathways may be delivered onto the elevator, detector devices arranged to be engaged by articles delivered onto the elevator from each of the respective pathways, each detector device responding to the pressure of an article thereagainst, and means operative to move the elevator to a different level with the block of articles resting thereon when all detectors are concomitantly engaged by articles standing on the elevator.

6. In combination in apparatus for introducing a filler block into a container, said block comprising independent, like articles arranged in parallel rows, all of which contain the same number of articles, means defining parallel pathways, in number equaling the number of rows in the filler block, said pathways being designed to direct articles moving along the pathways to a transfer station, a vertically movable elevator comprising a grid having a horizontal upper surface of a size and shape to receive and support articles to form the block, said elevator, when disposed at the transfer station, having its upper surface substantially at the level of the delivery ends of the pathways and with one edge juxtaposed to the delivery ends of the pathways, a substantially vertical guard depending from said edge of the elevator, the guard being of a transverse width to cover the ends of all pathways when the elevator is raised from the transfer station, stationary article-positioning blades which project up through the grid when the elevator is in the receiving position and means for raising and lowering the elevator.

7. In combination in apparatus for introducing a filler block into a container, said block comprising independent, like articles arranged in parallel rows, all of which contain the same number of articles, parallel spaced guides defining paths corresponding to the number of rows in the desired block, conveyor means operative to advance articles in succession along each path, means for supporting an open-sided container, at a level different from that of the conveyor, an elevator comprising a grid which, at times, is disposed at a level such that it may receive articles from

the several paths thereby to constitute the desired block, means for moving the elevator vertically to bring the block to the level of the container support, stationary article-aligning means extending up through the grid when the latter is in the receiving position, and means to discharge the block from the elevator into the container.

8. In combination in apparatus for introducing a filler block into a container, said block comprising independent, like articles arranged in parallel rows, all of which contain the same number of articles, a conveyor having a horizontal run constituting a support for articles, a plurality of fixed, parallel, spaced guides above said conveyor run, defining paths, in number equal to the number of rows of articles in the desired block, extending lengthwise of the conveyor and along which articles are moved by the conveyor, means for supplying articles to the several paths, a support for an open-sided container, said support being in a plane spaced from that of the conveyor path, a vertically movable article carrier designed, when at a receiving level, to receive articles from the several paths so as to constitute the desired block, a fixed spacer, aligned with each of said parallel guides, disposed above the support when the latter is at the receiving level, means for moving the carrier to a delivery level thereby to dispose said block at the level of the plane of the container support, and means operative to push the block of articles from the carrier into a container resting on the support.

9. In combination in a machine for assembling individual articles to form a filler unit and for loading said unit into a container, means for advancing individual articles in parallel rows toward a loading station, a vertically movable elevator arranged to receive a load of said articles at the loading station, a horizontally movable pusher for ejecting the load from the elevator, a fixed container-filling funnel, a horizontally movable impeller operative to advance a container so as partially to telescope it over the smaller end of the funnel, a power-driven shaft having cams thereon, and means actuatable by the cams on the cam shaft in properly timed relation to actuate the impeller, the motor and the pusher so as first to impel a container into operative relation to the filling funnel, then to raise the elevator to unloading position and then to operate the pusher to eject the load from the elevator and through the funnel into the container.

10. In combination in a machine for assembling individual articles to form a filler unit and for loading said unit into a container, means for advancing individual articles in parallel rows toward a loading station, a vertically movable elevator arranged to receive a load of said articles at the loading station, a horizontally movable pusher for ejecting the load of articles, as a unit, from the elevator, means for actuating the pusher, means for moving the elevator up from the loading station to an unloading position, movable supporting means for holding an open-sided empty container in load-receiving position at the unloading station, and means, including a detector, responsive to the weight of the filled container, after the pusher has projected the load from the elevator into the container, thereby to prevent another advance movement of the pusher until the filled container has been removed from load-receiving position.

11. In combination in a machine for assembling individual articles to form a filler unit and for loading said unit into a container, means for

advancing individual articles in parallel rows toward a loading station, a vertically movable elevator arranged to receive a load of said articles at the loading station, a horizontally movable pusher for ejecting the load, as a unit, from the elevator without disturbing the relative positions of the articles constituting the load, a fixed carton-filling funnel over whose smaller end an empty carton may be partially telescoped in readiness for the introduction of a filler load, a power-driven shaft, a lever, means connecting the lever to the elevator whereby rocking of the lever moves the elevator up and down, a second lever, a rack connected to said latter lever for reciprocating movement, means for transmitting motion from the rack to the pusher, and means carried by the shaft for actuating the two levers in properly timed relation.

12. In combination in a machine for assembling individual articles to form a filler unit and for loading said unit into a container, means for advancing individual articles in parallel rows toward a loading station, a vertically movable elevator arranged to receive a load of said articles at the loading station, a horizontally movable pusher for ejecting the load of articles, as a unit, from the elevator, a pair of parallel horizontally movable rack bars constituting supporting means for the pusher, a gear meshing with each rack bar, a transverse shaft to which said gears are fixed, a pinion fixed to the shaft, a reciprocable rack bar having teeth which engage said pinion, a lever, means connecting the lever to said latter rack bar, and means carried by the shaft for rocking the lever.

13. In combination in a machine of the class described having means for advancing independent articles in rows to a loading point, a vertically movable elevator arranged to receive a load of said articles at the loading point, fixed parallel walls separating the rows of articles as they approach the elevator, and fixed blades which constitute in effect extensions of said several walls and which are operative to keep the articles in separate rows as the articles are delivered onto the elevator.

14. In combination in a machine of the class described having means for advancing independent articles in rows to a loading point, a vertically movable elevator arranged to receive a load of said articles at the loading point, fixed parallel walls which keep the aforesaid rows separate as they approach the elevator, the latter having openings in its floor which are in the planes of the respective walls, and fixed separator elements projecting up through said openings in the elevator floor while the elevator is in the loading position and which are operative to keep the articles in the aforesaid rows as they are delivered onto the elevator.

15. In combination in a machine for assembling individual articles to form a filler unit and for loading said unit into a container, means for advancing individual articles in parallel rows toward a loading station, a vertically movable elevator arranged to receive a load of said articles at the loading station, a horizontally movable pusher for ejecting the load from the elevator, the elevator having a series of parallel slots in its floor, and fixed separator blades extending up through the slots when the elevator is in the load-receiving position, said blades being operative to keep the articles in orderly rows as they are delivered onto the elevator.

16. In combination in apparatus for introduc-

ing a filler block into a container, said block comprising independent, like articles arranged in parallel rows, all of which contain the same number of articles, fixed parallel rails defining a plurality of parallel paths, in number equal to the number of rows of articles comprised in the desired block, means for moving articles along the several paths, means for supplying articles to the several paths, an oscillatory blade aligned with each rail and located at the receiving ends of the paths, and power driven means for oscillating the blades in out-of-time relation thereby to prevent jamming of the articles as they approach the entrances to the several paths.

17. In combination in apparatus for introducing a filler block into a container, said block comprising independent, like articles arranged in parallel rows, all of which contain the same number of articles, fixed parallel rails defining a plurality of parallel paths, means for moving articles along the several paths, movable walls defining the sides of a distributing chamber from which articles enter the several paths, each wall being pivoted adjacent to the receiving end of one, respectively, of the outermost guide rails, said walls converging toward each other, means for delivering articles into the space between the nearer ends of said walls, and resilient means urging the free ends of the walls toward each other.

18. In combination in a machine for assembling individual articles to form a filler unit and for loading said unit into a container, means for advancing individual articles in parallel rows toward a loading station, a vertically movable elevator arranged to receive a load of said articles at the loading station, a horizontally movable pusher for ejecting the load from the elevator, a power-driven shaft, means including a one-revolution clutch, actuatable by the shaft, for raising and lowering the elevator, means actuatable by the shaft for reciprocating the pusher, an electrically actuated device for activating the clutch, and switch means for controlling the supply of current to said device, said switch means being so constructed and arranged as to close the circuit of said electrically actuated device only when a full load of articles has been delivered onto the elevator.

19. In combination in a machine for assembling individual articles to form a filler unit and for loading said unit into a container, means for advancing individual articles in parallel rows toward a loading station, a vertically movable elevator arranged to receive a load of said articles at the loading station and to enter said articles into a spacer grid positioned above the elevator, a detector responsive to the presence of a grid properly placed to receive the articles, a horizontally movable pusher for ejecting the load from the elevator, means for positioning an open-sided empty carton in readiness to receive a load from the elevator, a power-driven shaft, means, including a one-revolution clutch, actuatable by the shaft for moving the elevator up from a load-receiving position to an unloading position, the floor of the elevator, when in the latter position, being substantially flush with the bottom of an empty carton held in the receiving position, a detector which is sensitively responsive to the presence of a carton in the load-carrying position, other detectors which are sensitively responsive to the presence of a full load on the elevator, a solenoid for actuating the clutch, and switch means controlling the supply of current to

15

the solenoid, said switch means being so constructed and arranged as to close the solenoid circuit only in response to the concomitant action of all of the said several detectors.
